(57) **CLAIM**

The ornamental design for a transfer system platform, as shown and described.

DESCRIPTION

FIG. 1 is a perspective view of a transfer system platform; FIG. 2 is a front elevation view of the transfer system platform of FIG. 1;

FIG. 3 is a rear elevation view of the transfer system platform of FIG. 1;

FIG. 4 is a right side elevation view of the transfer system platform of FIG. 1;

FIG. 5 is a left side elevation view of the transfer system platform of FIG. 1;

FIG. 6 is a top plan view of the transfer system platform of FIG. 1; and,

FIG. 7 is a bottom plan view of the transfer system platform of FIG. 1.

The broken lines in the figures do not form a part of the claimed design.
